(57) **CLAIM**

The ornamental design for a foot mat, as shown and described.

DESCRIPTION

FIG. 1 is a perspective view of the foot mat in accordance with a first embodiment of the Design;

FIG. 2 is a top view of the foot mat of FIG. 1;
FIG. 3 is a bottom view of the foot mat of FIG. 1;
FIG. 4 is front view of the foot mat of FIG. 1;
FIG. 5 is a rear view of the foot mat of FIG. 1;
FIG. 6 is a right-side view of the foot mat of FIG. 1;
FIG. 7 is a left-side view of the foot mat of FIG. 1;
FIG. 8 is a perspective view of the foot mat of FIG. 1 shown in its environment;
FIG. 9 is a perspective view of the foot mat in accordance with a second embodiment of the Design;
FIG. 10 is a top view of the foot mat of FIG. 9;
FIG. 11 is a bottom view of the foot mat of FIG. 9;
FIG. 12 is front view of the foot mat of FIG. 9;
FIG. 13 is a rear view of the foot mat of FIG. 9;
FIG. 14 is a right-side view of the foot mat of FIG. 9;
FIG. 15 is a left-side view of the foot mat of FIG. 9;
FIG. 16 is a perspective view of the foot mat of FIG. 9 shown in its environment;
FIG. 17 is a perspective view of the foot mat in accordance with a third embodiment of the Design;
FIG. 18 is a top view of the foot mat of FIG. 17;
FIG. 19 is a bottom view of the foot mat of FIG. 17;
FIG. 20 is front view of the foot mat of FIG. 17;
FIG. 21 is a rear view of the foot mat of FIG. 17;
FIG. 22 is a right-side view of the foot mat of FIG. 17;
FIG. 23 is a left-side view of the foot mat of FIG. 17;
FIG. 24 is a perspective view of the foot mat of FIG. 17 shown in its environment;
FIG. 25 is a perspective view of the foot mat in accordance with a fourth embodiment of the Design;
FIG. 26 is a top view of the foot mat of FIG. 25;
FIG. 27 is a bottom view of the foot mat of FIG. 25;
FIG. 28 is front view of the foot mat of FIG. 25;
FIG. 29 is a rear view of the foot mat of FIG. 25;
FIG. 30 is a right-side view of the foot mat of FIG. 25;
FIG. 31 is a left-side view of the foot mat of FIG. 25; and,
FIG. 32 is a perspective view of the foot mat of FIG. 25 shown in its environment.

The evenly dashed broken lines depicting a user's feet in the Figures represent environment and form no part of the claimed design. The remaining evenly dashed broken lines depict portions of the article that form no part of the claimed design. The shading lines in FIGS. 3, 11, 19 and 27 form no part of the claimed design.

(Continued)

part of the design. FIGS. 1-2, 4-10, 12-18, 20-26, and 28-32 depict the design with a textured soft surface.
